[57] CLAIM

The ornamental design for a game box with individual pivotable pegs, as shown and described.

DESCRIPTION

FIG. 1 is a front elevational view of the game box with individual pivotable pegs showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross sectional view taken on line 7—7 of FIG. 5; and,

FIG. 8 is a cross sectional view taken on line 8—8 of FIG. 5.

The broken line showing of the words MUMBLEE PEG and CASH BOX, on FIG. 5, are for illustrative purposes only and forms no part of the claimed design.
